[57] ABSTRACT

A tunneling machine is disclosed which includes a cutter head rotatable in a first direction and in a second direction opposite the first direction. Inside roller cutters and gage (or outside) roller cutters are mounted on the head for cutting or crushing the end face of the tunnel. Each gage cutter is provided with a novel gage scraper means for clearing materials from the path of the gage cutter whether the head is rotated in the first or in the second direction.

GAGE SCRAPER FOR BIROTATIONAL TUNNELING MACHINES

BACKGROUND OF THE INVENTION

Tunneling machines generally include a support frame which is anchored in the tunnel and a rotatable cutter head. Roller cutters are mounted on the head, and rotation of the head causes the cutters to travel about the end face of the tunnel with rolling contact to cut or crush the formation encountered in a well-known manner. The cutters include inside cutters and cutters which travel about the radially outermost portion of the tunnel end face adjacent the cylindrical tunnel wall, the latter of which are known as gage cutters.

In order to protect the gage cutters, it is now known that gage scraper means can be provided which include a blade resiliently mounted on the head slightly in advance of each gage cutter. One such gage scraper means is shown in U.S. Pat. No. 3,674,314 granted to Joseph V. Scaravilli, and another is shown in U.S. Pat. No. 3,722,957 granted to Larry L. Snyder and James R. Matlack.

It is also known that in some instances it is desirable to rotate the head of the tunneling machine first in one direction for a period of time and then in the opposite direction for a period of time. On such birotational tunneling machines, gage scraper means have not heretofore been used in association with the gage cutters. This is because, although such gage scraper means would clear materials from the path of the gage cutter in the manner disclosed in the above referenced United States Letters Patent when the head of the tunneling machine is rotated in a direction so that the gage scraper means leads the gage cutter, the gage scraper means would not clear materials from the path of the gage cutter but instead would bend and break or would accumulate formation particles between the blade and the gage cutter when the head is rotated in the opposite direction.

SUMMARY OF THE INVENTION

These and other problems and disadvantages of prior art birotational tunneling machines are overcome by the present invention, which provides a birotational tunneling machine having a novel gage scraper means for clearing materials from the path of the gage cutter whether the head is rotated in the first direction or in the second direction.

The invention provides a tunneling machine which includes a cutter head rotatable in a first direction and in a second direction opposite the first direction. A roller cutter is mounted on the head for engaging an end face of a tunnel with rolling contact. The scraper means includes a first novel scraper mounted on one side of the roller cutter leading the roller cutter when the head rotates in a first direction, and a second novel scraper mounted on the other side of the roller cutter and leading the roller cutter when the head rotates in the second direction.

Each of the first and second scrapers includes a blade for clearing materials from the tunnel surface when leading the roller cutter. Each of the first and second scrapers also includes a mounting means for moving its associated blade away from the tunnel surface to prevent bending or breaking and to prevent the accumulation of formation particles between the blade and the

gage cutter when the scraper follows the roller cutter. The mounting means includes a first assembly rigidly secured to the head, a second assembly pivotally mounted on the first assembly, and a third assembly which carries the blade pivotally mounted on the second assembly.

BRIEF DESCRIPTION OF THE DRAWINGS

These and other aspects and advantages of the present invention are incorporated in the preferred embodiment of the invention shown in the accompanying drawings, wherein:

FIG. 1 is a schematic perspective view of a tunneling machine according to this invention;

FIG. 2 is a perspective view of one of the gage scrapers of the gage scraper means of the tunneling machine shown in FIG. 1;

FIG. 3 is an exploded perspective view showing the three major assemblies of the gage scraper shown in FIG. 2;

FIG. 4 is a side elevational view taken along reference view line 4—4 of FIG. 2, with the blade shown in phantom in a following displaced position;

FIG. 5 is a side elevational view taken along reference view line 4—4 of FIG. 2, with the blade shown in phantom in a leading displaced position; and

FIG. 6 is a rear elevational view of the gage scraper shown in FIG. 2.

DETAILED DESCRIPTION OF THE DRAWINGS

Referring now to the drawings in greater detail, FIG. 1 shows a birotational tunneling machine 10 which may be of any basic configuration and mode of operation, such as that shown in U.S. Pat. No. 3,383,138 to Victor J. Scaravilli et. al., the specification of which is incorporated herein by reference. The tunneling machine 10 includes a cutter head 11 which is rotatable in the clockwise direction and in the counterclockwise direction. In usage the cutter head 11 is rotated in one direction for a period of time and then is rotated in the opposite direction.

The cutter head 11 carries a plurality of inside saddles 12, only two of which are shown in FIG. 1, and each inside saddle 12 carries an inside roller cutter 13. The cutter head 11 also carries a plurality of gage saddles 14 only one of which is shown in FIG. 1, and each gage saddle 14 carries a gage roller cutter 15 which cuts the outermost portion of the tunnel end face adjacent the cylindrical tunnel wall. The inside roller cutters 13 and the gage roller cutters 15 may be of any well-known type, and the inside roller cutters 13 and gage roller cutters 15 roll about the tunnel end face as the cutter head 11 rotates to cut or crush the formation which is encountered. The tunneling machine 10 as described to this point is now well known in the prior art.

According to the principles of the present invention, each of the gage cutters 15 is provided with a gage scraper means 17 for clearing materials from the path of the gage cutter 15 when the cutter head 11 is rotated in the clockwise direction and when the cutter head 11 is rotated in the counterclockwise direction. Each of the inside cutters 13 could if desired also be provided with a scraper means identical to the gage scraper means 17, but the scraper means 17 is particularly useful with the gage cutters 15, since the gage cutters 15 may encounter formation particles projecting from

both the end face of the tunnel and from the cylindrical tunnel wall.

The gage scraper means 17 includes a first scraper 18 and a second scraper 19. The first scraper 18 leads the roller cutter 15 when the cutter head 11 is rotated in the clockwise direction as viewed from the rear of the tunneling machine 10 facing forwardly and follows the roller cutter 15 when the cutter head 11 rotates in the counterclockwise direction as viewed from the rear of the tunneling machine facing forwardly. Similarly, the second scraper 19 leads the roller cutter 15 when the cutter head 11 rotates in the counterclockwise direction and follows the roller cutter 15 when the cutter head 11 rotates in the clockwise direction.

The first and second scrapers 18 and 19 are structurally mirror images as shown in FIG. 1, and the structural details of the first scraper 18 are shown in FIGS. 2 through 6 of the drawings.

As best shown in the exploded view of FIG. 3, the scraper 18 includes a first assembly 23, a second assembly 24, and a third assembly 25. Although the assemblies 23, 24 and 25 are each made of several separate pieces fastened together in the presently preferred embodiment, the term "assembly" as used herein also includes a single piece construction.

The first assembly 23 includes a mounting plate 26 which is welded to the cutter head 11, a first side plate 27, and a second side plate 28. The plates 26, 27, and 28 are all welded together as shown in the drawings. The first assembly 23 also includes a tubular pivot member 29 which is welded to the plate 27 for pivotally securing the second assembly 24 to the first assembly 23 in a manner described in more detail below. The first assembly 23 also includes a tubular spring retainer 30 and brackets 31 and 32, all of which are welded in place as shown.

Still referring to FIG. 3, the second assembly 24 includes a generally flat rectangular pivot plate 37 having tubular pivot members 38, 39 and 40 welded to the ends thereof. The pivot plate 37 also includes a hole 41 extending through the pivot plate 37 and a spring retainer 42 (which is identical to the spring retainer 30 of the first assembly 23) welded to the bottom side of the pivot plate 37 around the hole 41. The spring retainer 42 cannot be seen in the perspective view of FIG. 3, but can be seen in FIGS. 4 and 5.

As further shown in FIG. 3, the third assembly 25 includes a support plate 48 having tubular pivot members 49 and 50 welded to one end thereof and stop members 51 and 52 welded to the pivot members 49 and 50, respectively. The third assembly 25 also includes a blade 53 bolted to the mounting plate 48 and having a first scraper edge 54 and a second scraper edge 55.

Referring now to the FIGS. 2 and 3 together, it is seen that the second assembly 24 is pivotally secured to the first assembly 23 by means of the pivot members 29, 38 and 39. A suitable pivot rod 56 (shown only in FIGS. 4 and 5 and preferably provided with sintered bronze bushings) extends through the pivot members 29, 38 and 39 to provide the pivotal connection, and the pivot rod 56 is held in place by end caps 58 welded to the outer ends of the pivot members 38 and 39. As explained in detail below, this first pivotal connection between the first assembly 23 and the second assembly 24 provides a pivot means for moving the blade 53 away from the cylindrical tunnel wall and away from the tunnel end face when the first scraper 18 is leading.

the roller cutter 15 to prevent damage to the first scraper 18.

Again referring to FIGS. 2 and 3 together, it is seen that the third assembly 25 is pivotally secured to the second assembly 24 by the pivot members 40, 49, and 50. A suitable pivot rod 57 (shown only in FIGS. 4 and 5 and preferably equipped with sintered bronze bushings) extends through the pivot members 40, 49 and 50 to provide this pivotal connection. End caps 58 are welded on the outer ends of the pivot members 49 and 50 to retain the pivot rod 57 in place. As explained in greater detail below, this pivotal connection between the third assembly 25 and the second assembly 24 provides a pivot means for moving the blade 55 away from the cylindrical tunnel wall and away from the tunnel end face to prevent damage to the first scraper 18 and to prevent accumulation of formation particles between the roller 15 and the first scraper 18 when the first scraper 18 follows the roller cutter 15.

Referring now to FIGS. 4 and 5, it is seen that a strong compression spring 62 extends between the first assembly 23 and the second assembly 24 to resist pivotal movement therebetween. A bolt 63 extends through the hole 41 in the pivot plate 37 and is threadably secured to a nut 64 which is welded to the bottom side of the side plate 28. The head of the bolt 63 limits the outward movement of the second assembly 24 to prevent the blade 53 from being pushed into voids in the tunnel by the spring 62 when the first scraper 18 is leading the roller cutter 15. Additionally, the bolt 63 can be threaded further into the nut 64 to push the second assembly 24 downwardly relative to the first assembly 23. This moves the blade 53 away from the cylindrical tunnel wall and away from the tunnel end face to permit changing the blade 53.

Again referring to FIGS. 4 and 5 together, it is seen that two identical relatively light tension springs 65 extend between the first assembly 23 and the third assembly 25 to urge the stop members 51 and 52 against the bottom surface of the plate 37. Only one of the springs 65 can be seen in FIGS. 4 and 5, but the other spring 65 is shown in phantom in FIG. 6. The springs 65 extend between a threaded rod 66 which is threadably secured to the bracket 32 at one end (FIG. 6) and to a nut 67 at its other end (FIG. 6). The other ends of the springs 65 are secured to suitable bolts 68 and 69 in the stop members 51 and 52, respectively (FIGS. 2 and 3).

Turning now to the operation of the gage scraper means 17, the operation of the first scraper 18 and of the second scraper 19 are identical, and only the operation of the first scraper 18 (shown in the drawings in FIGS. 2 through 6) will be described in detail.

The first scraper 18 is rigidly secured to the cutter head 11 by welding the mounting plate 26 to the cutter head 11. In this manner, the first assembly 23 moves with the cutter head 11 under all conditions and there is never any relative movement between the first assembly 23 and the cutter head 11.

When the tunneling machine 10 is rotated about the tunnel end face, the position of the first scraper 18 relative to the roller cutter 15 and relative to the tunnel is shown in FIG. 6. In this position, the first scraper edge 54 is pushed against an end face 69 of the tunnel and the second scraper edge 55 is pushed against the cylindrical wall 70 of the tunnel by the compression spring 62.

When the cutter head 11 is rotated in the clockwise direction as viewed from the rear of the tunneling machine 10 facing forwardly so that the first scraper 18 leads the roller cutter 15, the spring 62 resiliently urges the scraper edges 54 and 55 of the blade 53 against their respective tunnel surfaces to clear materials from the path of the gage cutter 15. When the cutter head 11 is rotated in this direction so that the first scraper 18 leads the roller cutter 15, a drag force will be exerted by the tunnel surfaces on the blade 53 in a direction indicated by the arrow shown in FIG. 5 and labeled "force when leading." The compression spring 62 is arranged so that it exerts a force urging the blade 53 against the tunnel surfaces and so that a drag force in the direction of the arrow shown in FIG. 5 when the scraper 18 is leading the roller cutter 15 of about 100 pounds will further compress the spring 62 and pivotally displace the second assembly 24 relative to the first assembly 23 as shown in phantom in FIG. 5. In this manner, the blade 53 is moved away from the cylindrical tunnel wall 70 and away from the tunnel end face 69 when a formation particle is encountered that cannot be removed by the first scraper 18 and to prevent damage to the first scraper 18.

This drag force exerted on the blade 53 when the first scraper 18 is leading the roller cutter 15 cannot rotate the third assembly 25 relative to the second assembly 24. This is because the drag force applied in this direction as indicated by the arrow in FIG. 5 urges the stop members 51 and 52 against the bottom surface of the plate 37, so that the stop members 51 and 52 provide a stop to prevent pivotal movement of the third assembly 25 relative to the second assembly 24 by a force exerted on the blade 53 in this direction.

When the first scraper 18 is leading the roller cutter 15 in this manner and a void is encountered in the tunnel, the compression spring 62 pushes the blade 53 into the void. However, the head of the bolt 63 engages the top surface of the plate 37 to limit such outward movement of the blade 53 so that the blade 53 cannot extend into the void sufficiently far to cause damage to the blade 53 when formation particles are again encountered. In this manner, the bolt 63 provides a stop to limit outward movement of the blade 53 to prevent damage to the first scraper 18 when voids are encountered in the tunnel surfaces.

When the cutter head 11 is rotated in the counterclockwise direction as viewed from the rear of the tunneling machine 10 facing forwardly, the first scraper 18 follows the roller cutter 15. When this occurs, the compression spring 62 still urges the blade 53 against the tunnel surfaces and a drag force is exerted on the blade 53 in the direction indicated by the arrow in FIG. 4 labeled "force when following." The tension spring 65 is arranged so that a light drag force in this direction of about 15 pounds overcomes the force of the springs 65 and pivots the third assembly 25 relative to the second assembly 24 as shown in phantom in FIG. 4. In this manner, the blade 53 is moved in a direction away from the tunnel surfaces so that the first scraper 18 cannot be damaged and so that material cannot accumulate between the roller cutter 15 and the first scraper 18 when the first scraper 18 is following the roller cutter 15. As the blade 53 is pivoted in the manner shown in phantom in FIG. 4 when the scraper 18 follows the roller cutter 15, the compression spring 62 will also push the plate 37 upwardly against the head of the bolt 63

so that the bolt 63 limits pivotal movement of the second assembly 24 relative to the first assembly 23 under these conditions.

Because the first scraper 18 and the second scraper 19 of the scraper means 17 are structurally mirror images and are functionally identical, the blade of the leading one of the scrapers 18 and 19 clears materials from the path of the roller cutter 15 while the blade of the following one of the scrapers 18 and 19 moves away from the tunnel surface to prevent damage to the following scraper and to prevent accumulation of materials between the following scraper and the roller cutter 15. Thus, when the cutter head 11 rotates in the clockwise direction as viewed from the rear of the tunneling machine 10 facing forwardly, the blade of the first scraper 18 clears materials from the path of the roller cutter 15 while the blade of the second scraper 19 is urged away from the tunnel surfaces by a light drag force. Similarly, when the cutter head 11 rotates in the counterclockwise direction, the blade of the second scraper 19 clears material from the path of the roller cutter 15 while the blade of the first scraper 18 is urged away from the tunnel surfaces by a light drag force. In this manner, the gage scraper means 17 which includes first and second structurally mirror image and functionally identical scrapers 18 and 19, overcomes the problems and disadvantages of the prior art discussed above.

What is claimed is:

- 30 1. A tunneling machine comprising a head rotatable in a first direction and in a second direction opposite said first direction, a roller cutter mounted on said head for engaging a surface of a tunnel with rolling contact, scraper means for clearing material from the path of said roller cutter when said head is rotated in either one of said first and second directions, said scraper means including a first scraper and a second scraper, said first scraper being mounted on one side of said roller cutter, said first scraper leading said roller cutter when said head rotates in said first direction and following said roller cutter when said head rotates in said second direction, said second scraper being mounted on the other side of said roller cutter, said second scraper leading said roller cutter when said head rotates in said second direction and following said roller cutter when said head rotates in said first direction, each of said scrapers including a blade for clearing materials from said tunnel surface when leading said roller cutter and mounting means for mounting said blade on said head, and each of said mounting means including means for moving its associated blade in a direction away from said tunnel surface when following said roller cutter by application of at least a first predetermined force exerted on said blade whereby bending and breaking of either of said first and second scrapers and accumulation of materials between either of said first and second scrapers and said roller cutter when following said roller cutter is avoided.
- 35 2. A tunneling machine as defined in claim 1 wherein each of said mounting means includes means for moving its associated blade away from said tunnel surface when leading said roller cutter by application of at least a second predetermined force exerted on said blade in a direction opposite said first predetermined force.
- 40 3. A tunneling machine as defined in claim 2 wherein said first predetermined force is less than said second predetermined force.
- 45
- 50
- 55
- 60
- 65

4. A tunneling machine as defined in claim 3 wherein each of said means for moving includes a pivot means and a spring.

5. A tunneling machine as defined in claim 1 wherein each of said mounting means includes a first assembly and a second assembly and a third assembly, said first assembly is rigidly secured to said head, said second assembly is pivotally mounted on said first assembly for pivotal movement relative to said first assembly, said third assembly is pivotally mounted on said second assembly for pivotal movement relative to said second assembly, and said third assembly carries said blade.

6. A tunneling machine as defined in claim 5 wherein each of said mounting means includes means for moving its associated blade portion away from said tunnel surface when leading said roller cutter by application of at least a second predetermined force exerted on said blade in a direction opposite said first direction, said first mentioned means for moving includes said pivotal mounting of said third assembly on said second assembly, and said second mentioned means for moving includes said pivotal mounting of said second assembly on said first assembly.

7. A tunneling machine comprising a head rotatable in a first direction and in a second direction opposite said first direction, a roller cutter mounted on said head for engaging a surface of a tunnel with rolling contact, a scraper leading said roller cutter when said head rotates in said first direction and following said roller cutter when said head rotates in said second direction, said scraper including a first assembly and a second assembly and a third assembly, said first assembly being rigidly mounted on said head, said third assembly including a blade for clearing materials from the path of said roller cutter when said head rotates in said first direc-

tion and said scraper leads said roller cutter, first pivot means pivotally mounting said second assembly on said first assembly, second pivot means pivotally mounting said third assembly on said second assembly, one of said pivot means moving said blade in a direction away from said tunnel surface when following said roller cutter by application of at least a first predetermined force exerted on said blade, and the other of said pivot means moving said blade in a direction away from said tunnel surface when leading said roller cutter by application of at least a second predetermined force exerted on said blade in a direction opposite said first predetermined force.

8. A tunneling machine as defined in claim 7 including a first spring for biasing said second assembly about said first pivot means in a direction toward said tunnel surface and a second spring for biasing said third assembly about said second pivot means in a direction toward said tunnel surface.

9. A tunneling machine as defined in claim 8 wherein said second assembly includes a generally flat plate, said first and second pivot means are disposed at opposite ends of said plate, and said blade is substantially perpendicular to said plate.

10. A tunneling machine as defined in claim 8 wherein said first spring extends between said first assembly and said second assembly.

11. A tunneling machine as defined in claim 8 wherein said second spring extends between said first assembly and said third assembly.

12. A tunneling machine as defined in claim 7 including stop means limiting movement of said third assembly relative to said second assembly when one of said predetermined forces is exerted on said blade.
